UNITED STATES PATENT OFFICE.

HANS MARTIN SIMONSON, OF PROVIDENCE, RHODE ISLAND.

DROP-HAMMER.

SPECIFICATION forming part of Letters Patent No. 761,923, dated June 7, 1904.

Application filed December 1, 1903. Serial No. 183,360. (No model.)

To all whom it may concern:

Be it known that I, HANS MARTIN SIMONSON, a citizen of the United States, residing at Providence, in the county of Providence and 5 State of Rhode Island, have invented a new and useful Improvement in Drop-Hammers, of which the following is a specification.

This invention has reference to an improvement in drop-hammers, and more particularly 10 to an improvement in the construction of the mechanism for operating the drop.

The object of my invention is to improve the construction of a drop-hammer and by 15 this improved construction to facilitate the operation of the machine.

My invention consists in the peculiar and novel construction of a drop-hammer whereby the drop is controlled by hand, foot, or automatically by the following mechanism: 20 a power-driven roll frictionally engaging with a roll on an eccentric shaft, said roll on the eccentric shaft forming a drum on which the drop-rope is wound to raise the drop, a vertical bar operatively connected with the eccentric shaft, a hand-lever engaging with the vertical bar, the operative movement of which raises the bar and partially rotates the eccentric shaft to disengage the friction-rolls and release the drop, a foot-lever operatively 25 connected with an eccentric shaft on which is a brake-bar adapted to engage with the periphery of the friction-roll forming the drop-rope drum and a pawl adapted to engage with a finger on the eccentric shaft of the drop-rope drum, a movement of the foot-lever operating to partially rotate the eccentric shafts to release the brake-bar and disengage the friction-rolls to release the drop, a catch on the vertical bar adapted to engage with a stud 30 on the frame when the bar is raised, an adjustable arm on the vertical bar, a pin on the drop, an adjustable cam-surface on the vertical bar, the upward movement of the drop operating to raise the vertical bar, which is held by the catch until released by the pin on the drop striking the cam-surface on the bar in the fall of the drop, means for exerting a 35 spring tension on the drop-rope, and other de-

tails of construction, as will be more fully set forth hereinafter.

Figure 1 is a front view of my improved drop-hammer, showing the operating parts in their relative positions with the drop down. Fig. 2 is a side view of the drop-hammer, showing the mechanism connecting the vertical bar and the foot-lever with the eccentric shafts controlling the driven friction-roll and the brake-bar. Fig. 3 is a top view of the drop-hammer, showing the driven friction-roll having the central drum for the drop-rope 60 and the outside drum for the rope of the spring-tension device. Fig. 4 is an enlarged detail sectional view taken on line X X of Fig. 1, showing the mechanism for operating the eccentric shafts. Fig. 5 is an enlarged 65 detail sectional view taken on line Y Y of Fig. 1, showing the construction of the friction-rolls, eccentric shafts, and brake-bar; and Fig. 6 is an enlarged detail sectional view taken on line Z Z of Fig. 1, showing the mechanism 70 for exerting a spring tension on the drop-rope. Fig. 7 is an enlarged detail view of the arm *h*, illustrating the operation of the pivoted pawl *k*.

In the drawings, *a* indicates the frame of the 75 machine; *b*, the drop; *c*, the driving-shaft; *d*, the pulley; *e*, the driving friction-roll; *f*, the driven friction-roll; *g*, the vertical operating-bar; *h*, the hand-lever; *i*, the clutch-bar; *k*, the foot-lever, and *l* the spring-tension device. 80

The frame *a* has the usual base *a'*, supporting the vertical frames *a'' a''*, having the ways *a'' a''* for the drop *b* and the bearings *a'' a''* and *a'' a''*. The cross-frame *a''* is secured to the top of the vertical frames *a'' a''* and has the bearings *a'' a''*. The drop *b* slides on the ways *a'' a''* and has the eye *b'*, to which the drop-rope *b''* is secured, and the pin *b''*, extending outward from the face of the drop. 85

The driving-shaft *c* is supported in the bearings *a'' a''* and carries the driving-pulley *d* on the left-hand end and the driving friction-roll *e* between the bearings *a'' a''*. The driven friction-roll *f* is supported on the eccentric shaft *f'*, which has the offset ends *f'' f''* supported 90 in the bearings *a'' a''*. The roll *f* is constructed 95

to form the depressed central drum f^3 , on which the drop-rope b^2 is wound to lift the drop, and the outside drum f^4 , on which the rope of the spring-tension device l is wound in the reverse direction.

The vertical operating-bar g has the lower end g^1 , shaped to form the catch g^2 , adapted to engage with the stud g^3 on the frame, the adjustable slide g^4 , having the cam-surface g^5 and secured by the bolt g^6 , the arm g^7 , adjustably secured by the bolt g^8 , and the contracted upper end g^9 , having the cross-pin g^{10} . The arm g^{11} is secured to the offset end f^2 of the eccentric shaft f' by the bolt g^{12} and has the vertical slots g^{13} g^{14} for the cross-pin g^{10} in its forward end.

The hand-lever h is pivotally secured by the screw h' to the stud h^2 on the right-hand vertical frame a^2 and has the curved arm h^3 , bearing on the side of the operating-bar g , and the curved arm h^4 , adapted to engage with the lower end of the operating-bar, as shown in Fig. 1. The coil-spring h^5 is secured to the arm h^4 and to the pin h^6 on the frame a^2 and exerts a spring tension on the arm h^3 to force the lower end of the bar g inward.

The brake i is pivotally supported on the eccentric shaft i' , having the offset ends i^2 i^3 supported in the bearings a^7 a^8 on the cross-frame a^6 . The bar i has the square edge i^3 and the roll i^4 . In its operative position the bar rests on the cross-frame a^6 , the square edge i^3 acting as a brake on the peripheral surface of the driven friction-roll f . To limit the movement of the brake-bar i , the curved arm i^5 , having the roll i^6 , may be used. This arm is removably secured to the top of the brake-bar by the thumb-screw i^7 , as shown in Fig. 5.

The foot-lever k is pivotally secured near its center to the stud k^1 on the base a' . Extending upward from the rear end of the foot-lever is the rod k^2 , pivotally secured to the foot-lever and to the arm k^3 , which is secured to the right-hand offset end i^2 of the eccentric shaft i' by the bolt k^4 , as shown in Fig. 2. The arm k^3 is also secured on the offset end i^2 by the bolt k^5 over the arm g^{11} and has the pawl k^6 pivotally secured to its end in a position to engage with the forwardly-bent end g^{15} of the finger g^{14} , forming a part of the arm g^{11} . The pawl k^6 is constructed to have a free upward movement in the downward movement of the arm k^3 , as shown in broken lines in Fig. 4, but forms a rigid extension of the arm k^3 in its upward movement.

The tension device l consists of the rope l' , the upper end of which is wound on the drum f^4 in a reverse direction to that in which the drop-rope b^2 is wound on the drum f^3 , the weight l^2 , secured to the lower end of the rope l' , the guide-arm l^3 , extending outward from the frame a^2 , and the coil-spring l^4 , placed intermediate the weight l^2 and the arm l^3 .

In the operation of my improved drop-ham-

mer the friction-roll e is revolved continuously 65 in the direction of the arrow by the pulley d . The friction-roll f by the partial forward rotation of the eccentric shaft f' is brought into frictional contact with the friction-roll e by the weight of the bar g and the arm g^{11} , 70 secured to the eccentric shaft f' , to revolve the friction-roll f and wind the drop-rope b^2 on the drum f^3 to raise the drop b . As the drop-rope b^2 is wound on the drum f^3 the rope l' of the friction device l is unwound from the 75 drum f^4 by the weight l^2 on the end of the rope. When the operation of the drop is controlled by hand or automatically, the curved arm i^5 is removed and the clutch-bar i is thrown out of engagement into the position 80 shown in broken lines in Fig. 5. The hand-lever h is now depressed. This brings the arm h^4 of the hand-lever into engagement with the lower end of the operating-bar g , raising the bar, and the arm g^{11} partially rotating the 85 eccentric shaft f' in a direction to release the friction-roll f from the friction-roll e , allowing the drop b to fall. By this novel arrangement of the mechanism the hand-lever h releases the drop at any point within its upward limit. When the operation of the drop is controlled by foot, the foot-lever k is depressed. This gives a partial upward rotation to the eccentric shaft i' through the rod k^2 and the arm k^3 on the eccentric shaft, lifting 90 the brake-bar i out of engagement with the friction-roll f and, through the pawl k^6 on the arm k^3 , engaging with the finger g^{14} on the arm g^{11} , partially rotates the eccentric shaft f' to release the friction-roll f from the friction-roll e and allows the drop to fall at any point desired. When the operation of the drop is controlled automatically, the upward movement of the drop brings the pin b^3 on the drop 95 into engagement with the arm g^7 on the operating-bar g , lifting the bar. The pin g^{10} on the upper end of the bar moves upward in the slot g^{13} in the arm g^{11} to allow the catch g^2 on the bar g to engage with the stud g^3 on the frame before the arm g^{11} is raised and the drop released, as described. The spring tension of the arm h^3 on the bar g holds the catch on the stud until the pin b^3 on the drop in its descent strikes the cam-surface g^5 on the bar g , releasing the catch from the stud and allowing the bar to drop down into its normal position. The arm g^7 is adjusted on the bar g to release the drop at any point desired. In the fall of the drop the rope l' of the tension device l is wound on the drum f^4 , compressing the spring l^4 when the blow is struck. As the drop rebounds from the blow the spring l' takes up the slack of the drop-rope b^2 , and the brake-bar i , engaging with the friction-roll f , holds the drop until the next upward 110 movement of the drop.

Having thus described my invention, I claim as new and desire to secure by Letters Patent—

1. In a drop-hammer, a power-shaft, a driving friction-roll on the power-shaft, a driven friction-roll on an eccentric shaft, a drum forming a part of the driven friction-roll on which the drop-rope is wound, a brake-bar adapted to engage with the peripheral surface of the driven roll, means for holding the driven roll in frictional contact with the driving-roll to raise the drop, means for holding the brake-bar in contact with the driven roll to hold the drop, and means for disengaging the driven roll from the driving-roll and the brake-bar from the driven roll to release the drop, as described.
- 15 2. In a drop-hammer, a power-shaft, a driving friction-roll on the power-shaft, a driven friction-roll on an eccentric shaft, a drum forming a part of the driven friction-roll on which the drop-rope is wound, a brake-bar on an eccentric shaft adapted to engage with the peripheral surface of the driven roll, means for holding the driven roll in frictional contact with the driving-roll to raise the drop, means for holding the brake-bar in contact with the driven roll to hold the drop, and means for operating the eccentric shafts to disengage the driven roll from the driving-roll and the brake-bar from the driven roll to release the drop, as described.
- 25 3. In a drop-hammer, a power-shaft, a driving friction-roll on the power-shaft, an eccentric shaft, a driven friction-roll on the eccentric shaft, a drum forming a part of the driven friction-roll, a drop, a rope secured to the drop and wound on the drum on the driven roll, a brake-bar on an eccentric shaft adapted to engage with the peripheral surface of the driven roll, means for holding the driven roll in frictional contact with the driving-roll to raise the
- 35 drop, means for holding the brake-bar in contact with the driven roll to hold the drop, means for operating the eccentric shafts to disengage the driven roll from the driving-roll, and the brake-bar from the driven roll to release the
- 40 drop, and means for taking up the slack of the drop-rope in the rebound of the drop from the
- 45

blow and holding the drop until the next upward movement of the drop, as described.

4. In a drop-hammer, the combination of mechanism for operating the drop, comprising a drum on which the drop-rope is wound, an auxiliary drum operating with the drop-rope drum, a brake adapted to hold the drop-rope drum, mechanism for taking up the slack of the drop-rope in the rebound of the drop consisting of a rope wound on the auxiliary drum in a reverse direction to that in which the drop-rope is wound and extending downward through an arm on the frame, a weight on the lower end of the rope, and a coil-spring intermediate the weight and the arm, and means for operating the brake to release the drop, as described.

5. The combination in a drop-hammer, of a power-shaft, a driving friction-roll on the power-shaft, an eccentric shaft, a driven friction-roll on the eccentric shaft having a drum on which the drop-rope is wound, the drop, and an auxiliary drum, a rope on the auxiliary drum extending downward through an arm on the frame, a weight on the rope, a coil-spring intermediate the arm and the weight, an arm on the eccentric shaft having an upwardly-extending finger, a vertical bar pivotally connected to the arm and having a catch, an adjustable arm, and an adjustable cam-surface, a stud on the frame, a pin on the drop, a hand-lever shaped to engage with the side and lower end of the vertical bar, a spring connected with the hand-lever and to the frame, an auxiliary eccentric shaft, a brake-bar on the auxiliary eccentric shaft, a roll on the brake-bar, an arm on the auxiliary eccentric shaft, a pawl on the arm, a foot-lever, means for disengaging the brake-bar, and means for limiting the movement of the brake-bar, as described.

In testimony whereof I have signed my name to this specification in the presence of two subscribing witnesses.

HANS MARTIN SIMONSON.
